PALLET RACK

William Schroeder, Evanston, Ill., assignor to Acme Steel Company, Chicago, Ill., a corporation of Illinois

Filed Nov. 21, 1960, Ser. No. 70,794

4 Claims. (Cl. 211—148)

This invention relates to the art of support structures, particularly to a collapsible shelf structure adapted for supporting palletized loads, of a type commonly referred to as a pallet rack.

The use of pallets or skids secured as supports for loads of all varieties of materials has been on the increase in recent years. The skid or pallet not only supports the load, but it permits the forks of a lift truck to be inserted below it in order to allow the palletized load to be conveniently transported from place to place as required. Due to the increased use of palletized loads, a definite need arose for a supporting structure which can support a maximum number of palletized loads in a minimum space at a minimum cost.

Structures for this purpose have been developed. They are generally in the form of vertical upright members joined together by horizontal side to side and front to back members which form an open type skeletal structure. The vertical members are made long enough to support the horizontal members at vertically spaced intervals to provide a multi-tiered structure for supporting palletized loads at different stacked levels. Also, the vertical members are spaced horizontally from each other by calculated amounts to establish bays of given length to accommodate a given number of palletized loads in a row without waste of space on the pallet rack structure. Within reason, the structures can be made of any length and any height depending upon the particular storage space available.

It seems that one of the most desirable requirements for a pallet rack structure is that it should be capable of being assembled and disassembled conveniently with a minimum of time and effort. It must also be rigid when assembled and not subject to accidental disassembly.

Another desirable feature is to have a minimum of parts and, if possible, no extra detachable parts which can be misplaced, such as connector pins.

It is therefore an important object of this invention to provide an improved pallet rack which can be assembled and disassembled conveniently with a minimum of time and effort, which is rigid when assembled and not subject to accidental disassembly, and which has a minimum of parts with no extra detachable parts, such as connector pins, which can be misplaced.

In order to achieve this objective a pallet rack structure is provided wherein there are only two basic components, the vertical supports or uprights and horizontal beams which are connected thereto. There are not other separate detachable parts. The connections between the uprights and the beams are by lugs on sleeves telescoped for sliding movement within the beams. The sliding movement of the sleeves enables the lugs to be withdrawn into the beam ends when the beams' ends are positioned between the uprights. This sliding movement also enables the lugs to be extended beyond the beam ends and into openings provided in the uprights where the lugs can be locked into place. With such an arrangement of permitting the lugs on the beams to be withdrawn into the beams, there are no projections from the ends of the beams which would prevent positioning the beams between the uprights. By allowing the lugs to be extended beyond the ends of the beams after the beams are positioned, this enables the beams to be connected at the sides of the uprights rather than along their front surfaces which is the most customary manner of connection in prior art devices.

2

Another object of the invention is to provide a locking pin which is integral with the telescoping sleeve and which is mounted on the sleeve along sloped slots for the purpose of providing a wedging action between the locking pin and the sleeve for creating a tighter connection between the beam and upright upon increased loading on the beam.

Other objects and advantages of the invention should be apparent upon reference to the accompanying drawings, in which:

FIG. 1 shows a perspective view of a partially cutaway pallet rack structure embodying the features of this invention;

FIG. 2 shows a partially cutaway enlarged sectional view of a portion of the pallet rack structure of FIG. 1 showing the region of connection between the end of a beam and an upright member;

FIG. 3 shows a partially cutaway and sectional elevational view along the line 3—3 of FIG. 2;

FIG. 4 shows a partially cutaway enlarged perspective view of the portion of the pallet rack structure of FIG. 1 showing the region of a connection between the end of a beam and an upright member;

FIG. 5 shows a sectional view along the line 5—5 of FIG. 3; and

FIG. 6 shows a top plan view of the end portion of a beam.

As viewed in FIG. 1, a typical support structure or pallet rack 1 consists of a pair of ladder-shaped upright frames 2 and 3 spaced apart from each other and joined together by means of horizontal beams 4, 5, 6 and 7. These beams are joined at their ends to the upright frames 2 and 3 in a manner hereinafter described. The upright frame 2 is also joined to the ends of other horizontal beams 8, 9, 10 and 11 which, although not shown, extend to an additional spaced upright frame similar to frames 2 and 3. In this manner the entire pallet rack 1 can be made any length required. Just as the beams 8, 9, 10 and 11 extend from the frame 2, other beams can extend in the opposite direction from the frame 3 so that the pallet rack can be extended in length in either direction.

Each of the upright frames 2 and 3 consists of a front upright 12 and a rear upright 13 joined together by horizontal front to back members 14 and 15 and diagonal braces 16 and 17. Naturally the lengths of the members 14, 15, 16 and 17 can be appropriately cut to space the uprights 12 and 13 as far apart as necessary to provide the proper span between the front beams 4 and 5 and the rear beams 6 and 7. Also, the uprights 12 and 13 can be made as tall as necessary in order to accommodate the required vertical spacing of the horizontal beams, as well as to permit positioning of as many vertically spaced beams as desired. Also, additional members similar to 14, 15, 16 and 17 can be added to provide sufficient rigidity and strength.

With the structure as shown in FIG. 1, the beams 5 and 6 provide a span across which pallets or other articles can span so that the beams act as their support at an upper level. Similarly the beams 4 and 7 provide a spanned support for pallets or other objects at a lower level. A pallet 18 is shown supported by the beams 4 and 7 and also a board 19. If continuous shelving is required so that objects will not fall through the spanned opening between the beams, a plurality of boards 19 can be positioned side by side along the beams to provide a continuous uninterrupted support for various shapes and sizes of objects.

The front to back members 14 and 15 and diagonal braces 16 and 17 are preferably welded at their ends to the uprights 12 and 13 in order to provide the completed ladder-shaped upright frames 2 and 3. This en-

ables the frames 2 and 3 to be shipped as integral units, thus saving erection time and also insuring a rigid structure which might not be obtained if nuts and bolts or other fastening means are used to secure these members together.

Each of the uprights 12 and 13 are provided with two rows of openings 20 extending along the entire length of the side walls 21 and 22 of the uprights. The openings 20 are equally spaced from each other by a fixed increment. These side walls 21 and 22 are positioned parallel to each other and are connected therebetween by front walls 23 which form the uprights into channel shapes. The side walls 21 and 22 are provided with flanges 24 and 25 which extend toward each other in a plane parallel to each front wall 21 of an upright. The flanges 24 and 25, the side walls 21 and 22 and the front wall 23 on each upright together provide a flanged channel shaped upright with four corners 26, 27, 28 and 29 which impart column strength and rigidity to the upright.

Even though different number designations have been given to the horizontal beams, they are all identical in structure and can be used interchangeably as front or back beams by merely rotating them 180 degrees end to end in a horizontal plane.

As shown in the drawings, a horizontal beam 6 consists of a rectangular shaped tube 31 composed of two channels 32 and 33 facing each other with their flanges 32a, 32b and 33a, 33b, respectively, overlapping each other to form the closed tube (FIG. 3). The overlapping flanges 32a, 32b, 33a and 33b are preferably welded together to maintain the channels 32 and 33 joined together and to impart strength to the assembled tube. Secured to the outside wall of the channel 33 is an L-shaped flanges 34 which is welded thereto and which acts as the support means for shelf material such as boards like board 19 shown in FIG. 1. When the beams are positioned, a flange 34 on one beam is positioned directly opposite a flange 34 on another beam so that opposite ends of the boards 19 or other similar parts can be suitably supported.

Within each end of the tube portion 31 of the beams, is a U-shaped sleeve 35 which is provided with an inside wall 35a connected between two side walls 35b and 35c to form the U-shape of the member 35. The free ends of the side walls 35b and 35c are provided with hooks 36 and 37 which are spaced vertically from each other in the normal position of the beam on its upright. These hooks 36 and 37 have their shapes imparted to them by means of open slots 36a and 37a extending inwardly from their lower portions. Each U-shaped sleeve 35 is provided with a U-shaped pin 38 which has a middle arm 39 connected between two side arms 40 and 41 to impart the U-shape to it. The arms 40 and 41 of this pin 38 project through canted slots 42 in the sleeve 35. There are four of these slots 42 in each of the sleeves 35, there being two in each of the side walls 35b and 35c and each of the two in a side wall are spaced vertically from each other while a slot in one side wall is positioned directly opposite a slot in the opposite side wall.

The spacing of the side walls 35b and 35c in each of the sleeves 35 is a little less than the spacing of the walls of the channels 32 and 33 which make up the tube 31 so that these side walls 35b and 35c are positioned close to the walls of the channels 32 and 33 when the sleeve 35 is telescoped within the tube 31. Each U-shaped pin 38 also has its portions 40 and 41 passed through four longitudinally extending slots 43 which are in the walls of the channel members 32 and 33, two in each member. Two washers 44 are fitted over the arms 40 and 41 of the pin 38 and are secured in place by welding or other fastening means in the positions shown best in FIGS. 3 and 5 for the purpose of retaining the pin 38 in place within the tube 31 and the sleeve 35.

With the sleeve 35 and the pin 38 assembled as described and shown in the drawings, the arms 40 and 41 are free to travel along the longitudinal slots 43 in the tube 31 and along the slots 42 of the sleeve 35. The movement of the pin portions along the slots 43 allows the sleeve 35 to be extended or retracted out of and into the tube 31 so that its hooks 36 and 37 either extend beyond the end 31a of the tube 31 or are withdrawn entirely into the tube 31. The movement of the pin in the slots 42 in reality occurs as movement of the sleeve 35 in an angular direction relative to the pin 38 at an angle determined by the cant or slope of the slots 42.

In order to assemble a horizontal beam 6 to an upright 12 or 13, the beam is extended horizontally with each of its ends positioned adjacent to two oppositely positioned upright members 12 or 13. The beam is temporarily supported at a level where the hooks 36 and 37 of the sleeves 35 on each end of the beam are in alignment with the respective openings 20 in the side walls 21 and 22 of the upright members 12 and 13. The spacing of these openings 20 vertically from each other is the same as that of the hooks 36 and 37, although the length of each opening 20 is more than the width of each of the hooks 36 and 37 so that the hooks can be positioned through these openings 20 without any difficulty.

With the beam positioned, as stated, with its ends between positioned uprights 12 or 13 and the hooks properly aligned with the openings 20, the connecting portion 39 of the pin 38 is manually gripped and the sleeve 35 on each end of the beam or tube is moved longitudinally of the beam toward the end of the beam by movement of the pin longitudinally of the beam. By moving the pin 38 to the left as viewed in FIG. 2, this causes the sleeve 35 to move to the left and extend the hooks 36 and 37 beyond the end 31a of the beam or tube 31 and through the openings 20 in the upright member 13. The slots 43 limit the travel of the sleeve 35 to the left as the pin arms 40 and 41 contact the left ends of the slots 43 at which time the pin arms 40 and 41 are, in effect, stationary projections relative to the beam or tube 31. When these hooks 36 and 37 are passed entirely through the openings 20, on both ends of the beam, support of the beam is removed so that it is allowed to drop downwardly and this allows the recesses 36a and 37a to fit down over the bottom shoulders or lips 20a of the openings 20. As the beam moves downwardly of its own weight the pin arms 40 and 41 are cammed against the side walls of the slots 42 to urge movement of the beam end 31a against the side wall 21 of the upright 13 so that the end 31a of the beam rests firmly against the side wall 21 of this upright 13. Even though the weight of the beam is ordinarily enough to provide a high degree of rigidity in the connection between the beam and the upright, additional weight on the beam by the loading of pallets onto the rack in its final assembled form, creates a tighter drawing up of the beam against the upright as the pin arms 40 and 41 are wedged more tightly down the inclines of the slots 42. This is a self-energizing locking action which is enhanced in this manner upon additional loading of the pallet rack.

Upon disassembly of the pallet rack, a force is applied upwardly from beneath the beam so that the pin arms 40 and 41 are urged up the inclines of the slots 42 to allow the hooks 36 and 37 to project a little more out from the end 31a of the beam. This releases the wedged locking condition and allows the beam to be raised further until the hooks 36 and 37 are clear of the shoulders 20a at the bottom of the openings 20 so that they can be withdrawn from the openings 20 upon manipulation of the pin 38 to the right, as viewed in FIG. 2.

From what has been shown and described it should be apparent that a pallet rack structure has been provided having only two basic separate components, viz., beams and uprights. The beams are readily positioned between

fixed spaced uprights without interference of connecting lugs when the sleeves 35 are retracted into the beams. After positioning it is a simple operation to extend the hooks 36 and 37 into the openings in the upright members to thereby secure the beams to the uprights. Also, removal of the beams from the uprights is similarly simple since a simple reverse procedure is required. The beams offer a complete unit with no extra parts, such as loose locking pins which are subject to being misplaced or lost, and the general simplicity of the structure and its assembly and disassembly allows erection and knock-down of the rack with a minimum of labor and time.

Although only a single embodiment of the invention has been shown and described, it should be apparent that the invention can be manufactured in still other ways without departing from the true scope of the invention as defined by the appended claims.

I claim:

1. A support structure comprising vertical uprights and horizontal beams, each upright being provided with a row of openings extending along at least one side wall of the upright, the beam having a sleeve telescoped within it and slidably mounted for movement longitudinally of the beam in two directions by means of a pin engaging at least one longitudinal slot in the beam, said sleeve being provided with a hook which projects from the end of the beam when the sleeve is moved in one direction and which is concealed in the beam when the sleeve is moved in the other direction, the projecting hook extending through one of said openings in the upright when the end of the beam is abutting the upright, said hook engaging a marginal lip of said one of said openings upon downward displacement of the beam, said pin also engaging at least one angular positioned slot in the sleeve so that downward movement of the beam urges the pin along the angular positioned slot to urge the hook in a direction into the beam and the end of the beam against the side wall of the upright to tighten the connection between the beam and the upright.

2. A combination of a horizontal beam, an upright, and a connection therebetween, said combination comprising, at least one hook, said hook being on connector means slidably mounted on the beam for movement from a position concealed within the beam to an extended position with the hook projecting longitudinally beyond the end of the beam, the upright having means for engaging the hook on the connector when it is in its extended position to connect the connector to the upright, a cam means reacting between the connector and the beam for urging the hook on the connector to be withdrawn into the beam to react against one side of the upright and thereby draw the end of the beam tightly against the opposite side of the upright upon downward

pressure on the beam, said cam means being a slanted slot in the connector engaged by an arm on the beam.

3. A combination of a horizontal beam, an upright, and a connection therebetween, said combination comprising, at least one hook, said hook being on connector means slidably mounted on the beam for movement from a position concealed within the beam to an extended position with the hook projecting longitudinally beyond the end of the beam, the upright having means for engaging the hook on the connector when it is in its extended position to connect the connector to the upright, said connector having a slanted slot engaged by an arm on the beam, said slanted slot being so directed that downward pressure on the beam causes the arm to be guided in the slanted slot to cause the end of the beam and the connector to be urged longitudinally tightly against the upright to provide a tight connection between the beam and the upright.

4. A combination of a horizontal beam, an upright, and a connection therebetween, said combination comprising, connector means including hooks, said connector means being slidably mounted on the beam for movement from a position concealed within the beam to an extended position projecting longitudinally beyond the end of the beam, the upright having openings through which said hooks of the connector means are passed for connecting the connector to the upright, said connector means having a first slot carried by an arm movable along the first slot, said arm also being engaged in a second slot in the beam extending longitudinally of the beam, said second slot allowing the arm to be moved longitudinally of the beam to move the connector means longitudinally of the beam between its concealed and extended positions, said first slot being so directed and acting as a cam surface for the arm to urge the end of the beam and said hooks to be clamped tightly against the upright in opposite directions to provide a tight connection between the beam and the upright upon downward pressure on the beam.
